(57) **CLAIM**

The ornamental design for a dispenser for semiochemical attractant, as shown and described.

DESCRIPTION

FIG. 1 is an upper-front perspective view of a dispenser for semiochemical attractant in accordance with the present design;

FIG. 2 is a lower-front perspective view of the dispenser for semiochemical attractant shown in FIG. 1;

FIG. 3 is a top plan view of the dispenser for semiochemical attractant shown in FIG. 1;

FIG. 4 is a bottom plan view of the dispenser for semiochemical attractant shown in FIG. 1;

FIG. 5 is a front view of the dispenser for semiochemical attractant shown in FIG. 1, which due to symmetry is the same as the left side, right side, and rear view;

FIG. 6 is a section view of the dispenser for semiochemical attractant shown in FIG. 1 through section 6-6 indicated in FIG. 3; and,

FIG. 7 is a section view of the dispenser for semiochemical attractant shown in FIG. 1 through section 7-7 indicated in FIG. 4.

1 Claim, 5 Drawing Sheets
